UNITED STATES PATENT OFFICE.

GEORGE W. BRITTON, OF HAMILTON, ONTARIO, CANADA, ASSIGNOR TO JAMES P. STEEDMAN, OF HAMILTON, CANADA.

ADJUSTABLE CONNECTER BETWEEN A SCALE BEAM AND SHELF LEVER OR PENDULUM.

Application filed May 13, 1925. Serial No. 30,127.

To all whom it may concern:

Be it known that I, GEORGE W. BRITTON, a subject of the King of Great Britain, and resident of the city of Hamilton, county of 5 Wentworth, Province of Ontario, in the Dominion of Canada, have invented certain new and useful Improvements in an Adjustable Connecter Between a Scale Beam and Shelf Lever or Pendulum, as described in 10 the following specification and illustrated in the accompanying drawings, that form part of the same.

The principal object of this invention is, to overcome the difficulties in aligning the 15 shelf lever or pendulum of a scale with the beam, thereby eliminating a great deal of machining and fitting and incidentally effecting a considerable saving in cost of construction, and further ensuring the maintenance of adjustments.

The principal feature of the invention consists in the arrangement of angularly adjustable bearing blocks upon either end of the shackle for connecting the beam with the 25 shelf lever or pendulum of the scale, whereby the shackle will operate freely and accurately with an angular set.

In the drawings, Figure 1 is an elevational view of a portion of the mechanism 30 of a dial scale showing the improved shackle arranged between the beam and the pendulum.

Figure 2 is an enlarged diagrammatic elevational view of the improved shackle showing 35 the offset alignment.

Figure 3 is a further enlarged perspective view of the improved shackle connection.

In the construction of scale mechanism it is a very difficult matter to arrange the main 40 beam and the shelf lever or pendulum, as the case may be, in perfect alignment and a very great amount of labor and expert manipulation is required in order to achieve a satisfactory result in the assembling of a 45 scale in such a manner that the shelf lever or pendulum and the main beam will cooperate in harmony.

The present invention has been devised to 50 eliminate the necessity for such exact adjustment in the setting of the beams and levers.

In the accomplishment of this result, the construction as herein shown, consists of pairs of blocks 1 and 2, the blocks of each

pair being rigidly secured to cross plates 3 and 4 respectively.

The blocks are provided with orifices 5 in which are arranged the V bearing blocks 6.

The paired blocks are arranged to straddle the beam 7 and the shelf lever or pendulum 8 respectively and the V blocks engage the usual knife edge supports 7' and 8'.

Secured to each of the cross plates is a plate 9 held tightly in position by means of screws 10 arranged either side of the central 65 socket member 11 in which the turn buckle rod 12 is secured.

Adjusting screws 13 are arranged at the outer ends of each of the plates 9. These screws are threaded in the plates 9 and abut 70 the face of the cross plates 3 or 4 and the screws 10 are tightened against the plates 9 to hold them securely.

It will be seen that by loosening the inner screws 10 and adjusting the screws 13 any 75 desirable tilt may be given to the plate 9, that is within the limits of the screws, and when the plate is adjusted the screws 10 may be tightened, thereby securing the rod 12 in an offset or angular position in relation to 80 the blocks.

This feature of adjustment enables the setting up of scales in such a manner that even though there may be some slight difference between the alignment of the main 85 scale beam and the pendulum or shelf lever, the bearing blocks on either end of the connecting shackle may be adjusted to correct the offset and to retain a fixed obliquity which will act as effectively as if the beam 90 were in perfect alignment.

What I claim as my invention is:—

1. A scale beam connecter, comprising the combination with the scale beam and pendulum, of a shackle having adjustable bearing blocks at the ends adapted to engage 95 said members.

2. A scale beam connecter, comprising the combination with the scale beam and pendulum members, of a shackle, and bearing 100 blocks secured to the ends of said shackle to engage said members and adapted to be adjusted in offset angular relation to the shackle.

3. A scale beam connecter, comprising the 105 combination with the scale beam and pendulum members, of bearing blocks adapted to straddle said members, plates abutting

2
said blocks, adjusting screws secured in said plates and engaging said blocks, fastening screws extending through said plates into said blocks, and a shackle rod connecting 5 said plates.

4. A scale beam connector, comprising the combination with the scale beam and pendulum members, of bearing blocks adapted to straddle said members, an adjustable 10 shackle rod, a plate rigidly secured to each

end of said shackle rod and having a pair of screw holes arranged at either side of the central connection, and threaded holes at the ends, adjusting screws secured in the outer threaded holes in the plates, and adjustable fastening screws extending through the inner holes in said plates and threaded in 15 said blocks.

GEORGE W. BRITTON.
